United States Patent Office.

JAMES T. BLISS AND JOSEPH D. DAVENPORT, OF NORTH PROVIDENCE,
RHODE ISLAND.

Letters Patent No. 98,548, dated January 4, 1870.

IMPROVED WEATHER-STRIP.

The Schedule referred to in these Letters Patent and making part of the same

To all whom it may concern:

Be it known that we, JAMES T. BLISS and JOSEPH D. DAVENPORT, both of North Providence, in the county of Providence, and State of Rhode Island, have invented a new and useful Door-Attachment for a substitute for thresholds; and we do hereby declare that the following specification, taken in connection with the drawings, making a part of the same, is a full, clear, and exact description thereof.

Figures 1 and 2 are sectional views of so much of a door and the jamb as will show the attachment, the door in fig. 1 being represented as ajar, and in fig. 2 as closed.

Figure 3 is a front view of the door and the attachment.

The only function which thresholds to interior doorways perform, is to prevent an open space remaining between the bottom rail of the door when closed and the floor, for the admission of cold draughts, it being necessary to trim the door short of the floor-level in order to enable it to swing, when opening, clear of the carpet.

A carpet, if the door is intended to be used, cannot be laid over the common raised threshold, as it is often desirable to do in order to improve the effect of two connecting rooms, which are covered with a carpet of the same pattern, and architects have long desired to devise some means which would dispense with the threshold, and yet prevent a draught-space under the door.

Our invention accomplishes this end, and consists in the attachment of a hinged plate to the bottom rail of the door, which, by the action of a spring, is made to lie flat against the edge of the bottom rail when the door is open, but will be turned down so as to close the space between the bottom rail and the floor when the door is closed.

Although the idea is borrowed from the well-known spring weather-strips used upon outside doors, and operates in a somewhat similar way, it is nevertheless to be distinguished from that device in its arrangement and adaptation to the purpose intended.

In the drawings—

A is the door;

B, the door-jamb; and

C, the floor, which may be carpeted or not, but if intended to be carpeted, allowance in hanging the door should properly be made therefor.

As seen in the different figures, the door is hung so as to clear the carpet or floor entirely when swinging.

A plate of thin metal, or other suitable material, D, is hinged, at a, to the edge of the bottom rail, and it is preferred, for appearance, to make a rebate in such edge of the rail to receive the plate and conceal the hinge.

Upon the edge of each stile of the door an opening is cut, which should be closed by a neatly-fitting plate capable of removal, if necessary.

At each extremity of the flap D, and at right angles therewith, or nearly so, are arms E, against which a spring, F, is made to bear. Both spring and arms are concealed by the covering plate above mentioned.

In each angle of the common rebate in the door-frame, an inverted inclined plane, G, is set.

The effect is apparent. Upon closing the door, the front edge of the flap D will strike the planes G, and, in consequence, such plate will be turned down, and close the space between the bottom of the rail and the carpet, and much more effectually exclude cold currents of air than the ordinary threshold would do. Upon opening the door, the action of the springs F will fold the flap D against the bottom of the rail.

We do not claim, broadly, a hinged flap, in combination with a door and a stop or inclined plane upon the jamb, to close the crack between the door and the threshold; neither do we broadly claim the use of the spring F, arranged to operate directly upon the hinged plate D; but

We claim, and desire to secure by Letters Patent—

The substitute for thresholds herein described, consisting of the combination of the horizontal hinged plate D with the arms E E, controlled by the spring F, and operated by the plane G, constructed, arranged, and operating substantially as described.

JAMES T. BLISS.

JOSEPH D. DAVENPORT.
